Claims priority, application Great Britain Feb. 22, 1973

Term of patent 14 years

Int. Cl. D19—08

U.S. Cl. D19—62

FIG. 1.

FIG. 2.

FIG. 3.

FIG. 4.

FIG. 1 is a front perspective view of a device for demonstrating the properties of X-rays showing my new design;
FIG. 2 is a side perspective view thereof;
FIG. 3 is a rear perspective view thereof; and
FIG. 4 is a top plan view thereof.

I claim:

The ornamental design for a device for demonstrating the properties of X-rays, substantially as shown.
